(57) CLAIM

The ornamental design for a display table, as shown and described.

DESCRIPTION

FIG. 1 is a perspective view of a display table showing my new design with legs shown in phantom;

FIG. 2 is a right side elevational view thereof, the left side elevational view being a mirror image of FIG. 2;

FIG. 3 is a front elevational view thereof, the rear elevational view being a mirror image of FIG. 3; and

FIG. 4 is a top elevational view thereof; and,

FIG. 5 is a bottom elevational view thereof.

The broken line representation in FIGS. 1-5 are exemplary and form no part of the claimed design.
